UNITED STATES PATENT OFFICE

145,996

DESIGN FOR A COMBINATION RADIO RECEIVER AND TIMER CLOCKCASE

Francesco Collura, New York, N. Y., assignor to
Telechron Inc., a corporation of Maine

Application January 21, 1946, Serial No. 125,803

Term of patent 7 years

(Cl. D56—4)

To all whom it may concern:

Be it known that I, Francesco Collura, a citizen of the United States, residing in New York, in the county of New York, State of New York, have invented a new, original, and ornamental Design for a Combination Radio Receiver and Timer Clockcase, of which the following is a specification, reference being had to the accompanying drawing, forming a part thereof.

The drawing is a front perspective view of a

combination radio receiver and timer clockcase showing my new design.

The two ends of the case are the same and the rear thereof is plain.

I claim:

The ornamental design for a combination radio receiver and timer clockcase, as shown and described.

FRANCESCO COLLURA.
